MECHANICAL FORK

Oliver H. Cooper, Burley, Idaho

Application March 7, 1947, Serial No. 733,146

2 Claims. (Cl. 294—124)

1

This invention relates to an improved construction of mechanical fork adapted for use in handling one or a plurality of bales of hay or straw or other materials and more particularly has reference to a novel trip release by means of which bale engaging elements of the fork may be released to swing to a position for releasing the bales therefrom while the fork is in motion or stationary and while the fork is located at a considerable distance from the operator.

Still another and important object of the invention is to provide a fork having trip means for permitting the fork to be moved by the weight of the load carried thereby to a released position and which will thereafter return to a position in which it can be latched with the load engaging elements in operative positions preparatory to engaging another load, to thus enable the fork to be operated entirely at a position remote to the operator, as for example, in an elevated position.

Various other objects and advantages of the invention will hereinafter become more fully apparent from the following description of the drawings, illustrating a preferred embodiment thereof, and wherein:

Figure 1 is a front elevational view of the mechanical fork shown in an engaged, operative position;

Figure 2 is an edge elevational view of the same and showing the fork in a released position as it will appear immediately after the release of a load therefrom;

Figure 3 is an enlarged front elevational view of the central portion of the fork and showing the trip and latch mechanism thereof;

Figure 4 is an edge elevational view showing the fork in an operative position and illustrating a load, in dotted lines, engaged thereby, and

Figure 5 is an enlarged cross sectional view taken substantially along a plane as indicated by the line 5—5 of Figure 3.

Referring more specifically to the drawings, the improved fork in its entirety is designated generally 6 and includes a supporting frame, designated generally 7, having a center rod 8 provided with an eye 9 at its outer end and having a web 10 secured to its inner end and provided with aligned sleeves or barrels 11 which are disposed in spaced relationship beyond the inner end of the rod 8. The frame 7 also includes diagonal braces 12 having corresponding ends secured to the rod 8, adjacent the eye 9 and which diverge therefrom and are provided at their opposite, remote ends with sleeves or

barrels 13 which align with the barrels or sleeves 11 and which are spaced outwardly therefrom a substantial distance.

A shaft 14 is journaled in the barrels 11 and 13 and is provided with an enlargement or collar 15 disposed intermediate the ends thereof and located between the sleeves or barrels 11. The rotatable shaft or rod 14 is provided with a plurality of tines 16 which project substantially radially therefrom in the same direction and which are provided with slightly upturned free end portions, as seen in Figures 2 and 4. The tines 16 are fixedly secured to the shaft 14 and are spaced relatively to one another, the shaft 14 being illustrated as provided with four tines 16, two of which are located between each sleeve 13 and the adjacent sleeve 11. However, it is to be understood that the tines may be spaced various distances apart and a fewer or greater number of tines may be employed.

An elongated U-shaped frame 17 includes two corresponding legs 18 having outturned free end portions 19 which terminate in upwardly or outwardly offset terminals 20 which are secured 30 in any suitable manner to the shaft 14, outwardly of the sleeves 11 and so that the portions 19 are disposed in outwardly spaced relationship to said sleeves for oscillatory movement therearound. The legs 18 are connected intermediate of their ends by a cross bar 21 having a squared or non-circular opening 22 therein which registers or aligns with a substantially diametrical bore 23 extending through the collar 15.

An elongated latch bolt 24 is provided with a non-circular end portion 25 which reciprocably and non-rotatably engages the opening 22 and which terminates in an eye 26 which is located in the frame 17 between the cross bar 21 and the bight portion 27 thereof. A portion of the latch bolt 24 is reciprocably disposed in the bore 23 of the collar 15 and an expansion coil spring 28 is disposed around a portion of the latch bolt 24 and has one end thereof seating on the upper side of the cross bar 21 and its opposite end bearing against a pin 29 which extends through the bolt 24 beneath and adjacent the collar 15 and by means of which said latch bolt is urged upwardly relatively to the frame 17. The lower end of the rod 8 is provided with a recess 30 to receive the opposite, upper end of the bolt 24 when the frame 17 is substantially in alignment with said rod 8 for latching the shaft 14 against rotation within the sleeves 11 and 13 and with 55 its tines 16 disposed substantially perpendicular

lar to the frame 7, as seen in Figure 4. A flexible element, such as a rope or cable, has an end 31 extending loosely through an opening 32 in the bight portion 27 and secured to the eye 26 so that a downward pull thereon will retract the latch bolt 24 against the action of its spring 28 for disengaging the upper end thereof from the recess 30 to permit the shaft 14 to turn in the sleeves 11 and 13, for a purpose to hereinafter become apparent.

The mechanical fork 6 may be supported by any suitable stationary or movable hoisting means, such as illustrated at 33 in Figure 2 and including a movable or stationary structure 34 provided with a supporting arm 35 for a bracket 36 in which a pulley 37 is journaled. A flexible member such as a rope or cable 38 is trained over the pulley 37 and has one end thereof secured to the eye 9; the other end, not shown, may be connected to any suitable draft means forming a part of the hoist 33, not shown.

Assuming that the latch bolt 24 is engaged in the recess 30, the fork 6 may be swung into a position so that each of the tines 16 will penetrate a bale of hay, straw or other material, one of which is indicated in Figure 4 in broken lines at 39. By operation of the hoisting mechanism 33, forming no part of the invention, the fork 6 may be elevated and transported for elevating and conveying the bales 39 engaged by the tines 16. The bales may be retained and engaged with the tines until they are moved and located in their new positions, after which by exerting an outward pull on the flexible member 31 the latch bolt 24 will be disengaged from the recess 30 to release the shaft 14 so that when an upward pull is exerted on the fork 6 by the flexible member 38 the tines 16 will assume the position of Figure 2 for disengaging themselves from the bale or bales 39. Likewise, the bales 39 may be dropped while in transit over a desired location by exerting a pull on the flexible member 31 to release the shaft 14, as previously described, so that the weight of the bales 39 will cause the tines 16 to assume the position of Figure 2 to allow the bales to slide readily therefrom. The weight of the frame 17 will tend to cause the parts to return to their positions of Figure 4 and by exerting a pull on the flexible member 31 to again retract the latch bolt 24, the frame 17 can be brought back to alignment with the rod 8 so that upon release of the pull on the flexible member 31 the latch bolt 24 will be returned by the spring 28 back into engagement with the recess

30 for relatching the fork 6 in its operative position and while still in a location remote to the operator.

Various modifications and changes are contemplated and may obviously be resorted to, without departing from the spirit and scope of the invention as hereinafter defined by the appended claims.

I claim as my invention:

10 1. In a fork of the character described, a frame, a fork having a head journaled in said frame, a latch including a reciprocable latch bolt, a support for said bolt secured at one of its ends to the fork head and projecting therefrom at an angle to the tines or teeth of the fork, said support being heavier than the fork tines to cause the support to assume a depending position substantially in the same plane as the frame for positioning the fork in an operative position, said

15 frame having a socket for receiving an end of the latch bolt for latching the fork in an operative position relatively to said frame, and spring means for urging the latch bolt to a projected position and for retaining it releasably in engagement with said socket to releasably retain the fork in an operative position.

20 2. A fork as in claim 1, and flexible means connected to and depending from the lower end of said latch bolt for retracting the bolt, against the action of said spring means, out of engagement with the socket whereby the fork is adapted to be rotated in the frame to a load releasing position by the weight of a load supported on the tine or tines of the fork, said flexible member extending longitudinally of the support and reciprocally through the end of the support disposed remote to the fork head.
